UNITED STATES PATENT OFFICE.

ELMER J. McMURTRY, OF NEW BRUNSWICK, NEW JERSEY.

DESIGN FOR A GAME-BOARD.

43,054.

Specification for Design.

Patented Sept. 24, 1912.

Application filed March 18, 1912. Serial No. 684,624. Term of patent 7 years.

To all whom it may concern:

Be it known that I, ELMER J. McMURTRY, a citizen of the United States, residing at New Brunswick, in the county of Middlesex and State of New Jersey, have invented a new, original, and ornamental Design for a Game-Board, of which the following is a specification, reference being had to the accompanying drawing, forming part thereof.

The figure is a plan view of the game board, showing my new design.

I claim:

The ornamental design for a game board, as shown.

ELMER J. McMURTRY.

Witnesses:

EUGENE W. MORRIS,
WILLIAM H. VAN DEURSER.
